UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,097,130.

Specification of Letters Patent. Patented May 19, 1914.

Application filed June 16, 1913. Serial No. 773,875.

To all whom it may concern:

Be it known that I, DAVID S. KENNEDY, a citizen of the United States, residing at Brooklyn, in the county of Kings and State of New York, have invented certain new and useful improvements in Typographical Machines, of which the following is a specification, reference being had therein to the accompanying drawing.

10 My invention relates to typographical machines such as Linotype machines of the general organization represented in Letters Patent of the United States, No. 436,582, to O. Mergenthaler, wherein circulating matrices are released from a magazine in the order in which their characters are to appear in print and then assembled in line, the composed line transferred to the face of a mold, the mold filled with molten metal to 20 form a slug or Linotype against the matrices which produce the type characters thereon, and the matrices thereafter returned through a distributing mechanism to the magazine from which they started. More 25 particularly, it relates to machines of this kind when equipped with a plurality of independently usable magazines, any one of which may be brought into operative relation to the assembling and distributing devices, as required.

In the particular form illustrated, a plurality of inclined magazines is mounted in a shift frame, whereby the selected one may be located in registration with the assembling and distributing mechanisms, and in addition the magazines are so arranged in the frame that they may be individually moved therein with reference to the frame and each other, each substantially in its own 40 plane, so as to bring it into and out of operative relation to the assembling devices. It follows that each change of magazines thus involves a triple movement: first, whereby the magazine in position is moved rearwardly to clear the assembling devices; second, the shifting of the magazines as a whole to bring a new magazine into alignment with the assembling and distributing mechanisms; and third, the individual movement of the selected magazine into operative engagement with the assembling devices. Numerous advantages are involved in this form of construction. For instance, each of the magazines is provided with its 55 own bank of escapements, and the individual

movement of the selected magazine brings its escapements directly over and in position to be actuated by the single series of reeds, which may thus be located directly beneath the escapements, or in other words, in the 60 most desirable position to operate them.

Other advantages and features of construction will be apparent from the description and the drawings hereinafter to be referred to.

In the accompanying drawings, I have shown my invention in preferred form and by way of example, and as applied to a Linotype machine. Obviously, many changes and variations may be made therein, and in 70 its mode of application, which will still be comprised within its spirit. Further, it may similarly be adapted to other forms of typographical machines, such as typesetters, typescasters, and the like, which handle type 75 or dies, instead of matrices as herein illustrated. Generally speaking, I desire it to be understood that I do not limit myself to any specific form or embodiment, except in so far as such limitations are specified in the 80 claims.

Referring to the drawings: Figure 1 is a side view, partly in section, of a portion of a Linotype machine, having my invention applied thereto; Fig. 2 is a somewhat similar 85 view, showing the parts in different position; Fig. 3 is an enlarged perspective detail of the shift frame; Fig. 4 is a top view, taken substantially at right angles to the inclined magazines; and Fig. 5 is a section 90 taken substantially on the lines 5-5 of Fig. 4.

Referring to the drawings, the matrices X are as usual stored in the several magazines A, which may be shifted as a whole to bring 95 any selected one into registration with the front plate C of the assembling mechanism, and with the channel entrance E, through which the matrices are delivered from the distributing mechanism D. Each magazine 100 A is also capable of movement relatively to the others, forwardly into operative relation to the assembling devices as shown in Fig. 1, and rearwardly to the position shown in Fig. 2, whereby it is cleared from the other 105 parts and the magazines may be shifted as a whole to another level.

Each magazine A is provided with its own bank of escapements B, whereby the release of the matrices X into the front plate C is 110

controlled. The pivoted escapements B are of the ordinary construction and require no specific description, being moved in one direction into engaging relation with the matrices by springs, and in the other direction to release the lowermost matrix by reeds F, the selection and actuation of which are governed from the keys G and keyboard mechanism G', all in the customary manner. As will be readily understood, the forward movement of the magazine A not only brings it into operative relation to the front plate C, but in addition locates its escapements B over the single bank of reeds F, the extent of movement being sufficient to enable the reeds to act upon the escapement levers at their rear portions beyond their pivots, so that the first or upward action of the reeds is availed of to release the lowermost matrix. The magazines A, three of which are shown by way of illustration in the drawings, are mounted in the frame H, which is guided as at H³⁰ in the main frame J, and may be shifted in any desired manner to bring a selected magazine into alignment with the assembling and distributing mechanisms. In the drawings such means are shown as comprising a link H' connected at one end to the center of the frame H, and at its other end to an arm H² upon the transverse rock shaft H³. On the end of the rock shaft is mounted the operating arm K, whereby the shaft may be turned and the frame H shifted, the arm K being provided with a pawl K' to engage the fixed sector K² to hold the parts in adjusted position. The shaft H³ also carries an arm H⁴ connected to the powerful spring H⁵, to counterbalance the weight of the frame H and the magazines carried thereby, and thus to minimize the manual effort necessary to shift them.

As previously stated, each magazine A is independently movable forwardly and rearwardly in the frame H, this being preferably accomplished (see Figs. 3, 4 and 5) by the employment of transverse supporting bars A' connected to the magazine and arranged to slide at their ends in longitudinal grooves H¹⁰ formed in the sides of the frame H. Two such bars A' are preferably employed in connection with the magazine, located respectively at the front and rear thereof. Each magazine is also provided with a transverse arresting or locking bar A³, immediately in the rear of the front supporting bar A', and with a slight space between them. The front bar A' is formed on its lower side with downward projection A² designed and adapted to cooperate with inwardly projecting portions H²⁰ formed at the sides of the frame H, and the bar A³ is formed with downward projections A⁴ similarly adapted to cooperate with the same projecting portions H²⁰.

In the position of the parts indicated in Figs. 2, 4 and 5, namely that occupied by the magazines at the time they are to be shifted, the projections A² of the bars A' are located behind the projections H²⁰ of the frame H, thereby holding the magazines against downward and outward movement. After the frame has been shifted to bring the desired magazine into alignment with the assembling devices, and it becomes necessary to move it forward into operative relation thereto, the magazine is lifted to disengage the projections A² from the projections H²⁰ (the width of the grooves H¹⁰ being sufficient to permit this action), when the magazine will slide forward and downward to the position indicated in Figs. 1 and 3, in which it will be held by the engagement of the projections A⁴ on the bar A³ with the frame projections H²⁰. The restoration of the magazine to its original position is effected by its rearward movement, it being noted that the inner corners of the projections A² and the outer corners of the projections H²⁰ are inclined or beveled to facilitate the passage of the bar A' thereover. The magazines A may be provided if desired with laterally extending handles N, whereby their individual manipulation and movement will be more conveniently effected.

The channel entrance E is pivotally mounted at E' on the main frame J, and a spring E² is connected thereto so as to hold the entrance E in operative relation to the distributing mechanism D and the magazine in use, as shown in Fig. 1. When a change of magazines is desired, and the one in use is therefore moved rearwardly, it swings the entrance or throat E about its pivot E' to the position shown in Fig. 2, it being noted that the relation of the spring E² to the pivot E' is such that the movement of the throat to either operative or inoperative position causes it to pass center, so that the throat will be held therein by the spring. It will be seen that the rearward movement of the magazine in the shift frame not only clears it from the assembling devices, but also from the channel entrance; so that the magazines are ready to be shifted without interference with the other parts.

As previously indicated, I have shown my invention only in preferred form and by way of example, and as applied to a linotype machine, but many modifications and changes therein will suggest themselves to those skilled in the art, without departure from its scope.

Having thus described my invention, its construction and mode of operation, what I claim and desire to secure by Letters Patent of the United States, is as follows:

1. In a typographical machine, the combination of a plurality of magazines, means for shifting them as a whole, and assembling

- devices, the said magazines being individually and independently movable into and out of operative relation to the assembling devices.
5. 2. In a typographical machine, the combination of stationary assembling devices, and a plurality of magazines movable relatively to the assembling devices in two distinct directions, one individually and independently toward and away from the assembling devices, and another as a whole transversely past the same.
10. 3. In a typographical machine, the combination of a plurality of inclined magazines, and a supporting frame to shift them vertically as a whole, the said magazines being movable individually and independently in a forward direction in said frame into operative position.
15. 4. In a typographical machine, the combination of assembling devices, a plurality of magazines, and a frame to support them in retracted position in the machine, the said magazines being slidably arranged in said frame so as to be movable individually and independently into operative relation to the assembling devices.
20. 5. In a typographical machine, the combination of assembling devices, and a plurality of magazines movable as a whole to bring any selected one into registration with the assembling devices, the said magazines being mounted so as to be individually capable of a further independent movement into operative relation thereto.
25. 6. In a typographical machine, the combination of assembling devices, a plurality of magazines to coöperate therewith, and a movable shift frame to support the magazines, the said magazines being individually and independently movable relatively to the frame into and out of operative relation to the assembling devices.
30. 7. In a typographical machine, the combination of assembling devices, a plurality of magazines to coöperate therewith, and a supporting frame to shift the magazines into and out of alinement with the assembling devices, the said magazines being individually and independently movable relatively to the frame into and out of operative relation to the assembling devices.
35. 8. In a typographical machine, the combination of assembling devices, a plurality of magazines to coöperate therewith, a supporting frame to shift the magazines into and out of alinement with the assembling devices, and means for holding the alined magazine in different positions in the frame without affecting the position of the other magazines, one in operative relation to the assembling devices and another out of operative relation thereto.
40. 9. In a typographical machine, the combination of a plurality of magazines movable as a whole to bring any selected one into position, and each individually movable in relation to the others, and a delivery entrance mounted independently of the magazines and adapted to be moved from its operative position by the individual movement of a magazine.
45. 10. In a typographical machine, the combination of a supporting frame, a magazine movable relatively thereto into and out of operative position, and a delivery entrance mounted independently of the magazines and to coöperate with the magazine when in its operative position, and adapted to be moved out of such coöoperative relation by the movement of the magazine from its operative position.

In testimony whereof I have affixed my signature in presence of two witnesses.

DAVID S. KENNEDY.
